UNITED STATES PATENT OFFICE.

BRITTON E. BYRD, OF DURHAM, NORTH CAROLINA, ASSIGNOR TO BYRD MANUFACTURING CO., OF DURHAM, NORTH CAROLINA.

KNOTTER.

1,002,495.

Specification of Letters Patent. Patented Sept. 5, 1911.

Application filed March 25, 1910. Serial No. 551,487.

To all whom it may concern:

Be it known that I, BRITTON E. BYRD, a citizen of the United States, residing at Durham, in the county of Durham and State of North Carolina, have invented a new and useful Knotter, of which the following is a specification.

This invention has reference to improvements in knotters, and more particularly in knotters designed to be used by hand for securing together the ends of threads, the structure being usually carried by the left hand of the operator and actuated by the thumb.

15 It is the object of the present invention to provide an improved construction wherein these parts may be readily stamped from sheet metal into the desired shape and readily and cheaply assembled.

20 The present invention is an improvement on the knotter shown and described in Letters Patent #934,389 granted to me on Sept. 14, 1909, and is directed more particularly to the clamping mechanism for the threads, 25 the knotter of the present invention being also modified in some respects over the knotter shown in the said Letters Patent in other particulars than in the clamping mechanism.

The invention will be best understood 30 from a consideration of the following detail description taken in connection with the accompanying drawings forming a part of this specification, in which drawings,—

35 Figure 1 is a view, with parts broken away, and on a somewhat enlarged scale, of a hand knotter embodying the present invention, the parts being shown in normal position. Fig. 2 is a view similar to the showing of Fig. 1 but with the parts in operative position. Fig. 3 is a perspective view with parts 40 in section of the clamp mechanism. Fig. 4 is a perspective view of a bracket co-acting with the clamp mechanism. Fig. 5 is a fragmentary detail view, showing the tying-bill shaft.

45 Referring to the drawings there is shown a casing or body portion 1 housing a portion of the actuating mechanism for a tying bill 2, but as these parts form no necessary part of the present invention it is deemed unessential to describe them in detail. At one end of the casing 1, that is the end remote from the tying-bill 2 there is a pin or arbor 3 carrying the angle end of a substantially triangular frame made up of a base

member 4, an arm 5 and a connecting part 6 which latter is preferably curved concentric with the arbor 3 and carries a suitable rack 7, or other driving means for the shaft 2^a of the tying bill 2 so that when the frame 60 is moved about the arbor 3 as a pivot the tying bill will be rotated in the usual manner. A spring 8 surrounding the arbor 3, and at one end engaging the arm 5 and at the other end engaging the casing 1, serves 65 to maintain the triangular frame in the inoperative position illustrated in Fig. 1. A thumb-piece 9 projects at the junction point of the members 4 and 6 of the frame so that by the application of a suitable force on said 70 handle member, usually by the thumb of the left hand of the operator, the frame may be moved about the arbor 3 as a pivot from the position shown in Fig. 1 to the position shown in Fig. 2, this resulting in a rotative 75 movement of the tying bill 2 and the movement of other parts to be described.

Fast to the casing 1 is a bracket 9^a and this bracket carries a handle member 10 which in turn is provided with a strap member 11 to receive the fingers of the hand of the operator, these parts being substantially such as shown in the aforesaid Letters Patent. The bracket 9^a is connected to the casing 1, preferably at the axis of the arbor 3, 80 by a brace 12 having the end adjacent to the casing 1 slotted, as shown at 13 so that the relation of the hand hold to the casing 1 may be adjusted within limits. The end of the bracket 9^a where connected to the casing 1 85 is so connected by a screw 14, being surrounded between the bracket 9^a and the corresponding face of the casing 1 with a sleeve 15 which operates both as a spacing sleeve and as an antifriction roller as will presently appear.

90 The clamp member of the knotter comprises a frame made up of two like parts 16 and 17, each comprising a central longitudinal member 18 formed on one side near one 95 end with an offset 19 through which there is formed an elongated slot 20 of such width as to receive the roller 15 without binding, the screw 14 also extending through the slot 20 of the two matching members 16 and 17 100 of the clamp. Each member 18 is joined at the ends to a strengthening piece 21 arching from one end to near the other of the central member 18. The two members 16 and 17 are spaced apart sufficiently to receive a 110

plane slide 22 terminating at one end normally beyond the arch 21 of each member 16-17, in a hook 23 and at the other end, coincident with the slots 20, with a lateral eye 24 through which the sleeve 15 passes, the member 22 being stamped out of a single piece of sheet metal. At an intermediate point the member 22 is provided with an elongated slot 25 through which is passed a pin 26 connected at the ends in the central members 18 of the two clamp members 16-17 securing these members together in spaced relation so that these members are sufficiently separated to receive the slide 22 while quite closely embracing the same. At the other end of the clamp remote from the end where is located the hook 23 the two members 16 and 17 are joined by a pin or rivet 27 which in turn secures the clamp member pivotally to a bracket 28, the other end of which is bent to embrace and be secured fast to the arm 5, in any appropriate manner. Since the screw 14 traverses the eye 24 of the slide 22, the latter remains in fixed relation to the bracket 9^a so far as any longitudinal movement is concerned but is free to turn about the longitudinal axis of the screw 14 with relation to said bracket.

When the frame made up of the members 4, 5 and 6 is turned about its pivot 3 by force applied to the thumb-hold 9, the bracket 28 participates in this movement and its free end moves through an arc concentric with the axis of the pin or arbor 3. The length of the bracket 28 and its relation to the arm 5 is such that its free end will move in an arc toward the screw 14 and then pass the same for a distance, the path leading between said screw and the pin or arbor 3. Since the free end of the bracket 28 is pivoted to the corresponding end of the clamp structure, made up of the frames 16 and 17, the corresponding ends of this clamp structure will be carried through a like path, approaching and then passing the screw 14. The result of this is that the frames 16 and 17 are given both a rotative movement about the axis of the screw 14 and a longitudinal movement with relation thereto, which movement is permitted by the slots 20. The other end of the clamping members 16 and 17 therefore rise through a path determined by the movement of the first named end of the clamping members with relation to the screw 14. The beginning of the movement of the frames 16-17 is in a line nearly coincident with the length of the members 18 of the clamp frames and this movement continues until these frames have approached the hook 23 and finally moved on each side of and in embracing relation thereto, this movement being permitted by the slot 25 traversed by the pin 26 and continues so long as the free end of the bracket 28 is moving in a nearly direct line

toward the pin 14. As soon however as the free end of the bracket 28 and the corresponding ends of the clamp frames cease to move in a nearly direct line toward the screw 14 but begin to move past the same then the other end of the clamp frame rises rapidly in a curved path nearly concentric with the axis of the screw 14.

The frame 1 on the side of the tying bill remote from that occupied by the clamp frame carries a thread-supporting hook 29. The thread to be tied is laid into the hook 29 and then across the tying bill 2 and through the hook 23 between the same and the arch members 21 of the frames 16 and 17 where they join the longitudinal members 18 adjacent to the hook 23. On now manipulating the actuating frame made up of the members 4, 5 and 6 by a force applied to the thumb-hold 9, the tying bill 2 is given a rotative movement and at the same time the frames 16 and 17 are moved along the slide 22 until the hook 23 has gripped the thread against the adjacent edges of the arch members 21, the tying bill having in the meantime made a partial rotation. As soon as the thread is clamped then the clamp member begins to rise, turning about the screw 14 as an axis. This serves to tighten the thread about the tying bill and when the clamp member has reached its limit of movement away from the tying bill the tension on the thread is sufficient to draw it on the tying bill which, in the meantime, has tied a knot in the two strands to be united.

While the member 22 has been termed a slide, the sliding movement is only relative since it only has a pivotal movement about the screw 14, while the other member of the clamp structure slides with relation to the screw 14 and with relation to the member 22.

What is claimed is:—

1. The combination with a tying bill and means for operating the same, of a two-part thread-clamp having its members mounted upon a common pivot and arranged for right-line reciprocatory movement in opposite directions, and a connection between one of the clamp members and the tying bill operating means, whereby arcuate movement of the latter in one direction will impart like movement in the other direction to the clamp-thread member with which it is connected and simultaneous right-line reciprocatory movement to the two clamp members throughout the arc traversed.

2. The combination with a tying bill and means for operating the same, of a two-part thread-clamp pivotally supported adjacent to the tying bill, and means actuated from the tying bill operating means for imparting arcuate and right-line reciprocatory movements to both of the members of the

thread-clamp in an opposite direction to the movement of the operating means.

3. A hand carried and manipulated knotter, having a support, a shaft rotatably mounted therein, a spring returned segment pivoted to one end of the support, coacting means carried by the segment and shaft to rotate the shaft, a finger-engaging arm to operate the segment, a tying bill arranged at one end of the shaft, a clamping member pivoted and slidable in the same plane, and comprising two self-contained parts, one of which is pivoted to the support, while the other is pivotally and slidably mounted with relation to the first part, and means for operably connecting the sliding part with the segment.

4. A hand carried and manipulated knotter, having a support, a shaft rotatably mounted therein, a segment pivoted to the frame, coacting means between the segment and the shaft to operate the shaft, means whereby the segment may be operated in one direction, a spring for returning the segment in the opposite direction, a tying bill mounted at the outer end of said shaft, a clamping member formed of two self-contained members, one of which is pivoted to the frame while the other is pivotally and slidably mounted with relation to the other member, and means for operably connecting said sliding member to the segment, whereby as the sliding member is lifted the pivoted member is lifted and the sliding member is moved outwardly to throw-off position.

5. A hand carried and manipulated knotter, having a support, a shaft mounted for rotation in the support, a tying bill carried by the outer end of the shaft, a gear formed on the shaft within the frame, a segment pivoted within the frame and provided with a rack surface for engaging the gear to rotate the shaft when the segment is moved,

a finger-engaging arm for operating the segment in one direction, a spring for returning the segment in the opposite direction, a clamping member formed in two parts, one of which constitutes a hook with a fixed pivotal point to the frame, and the other having a sliding movement around the pivot to coact with the hook, and means for connecting the sliding member to the segment, whereby as the segment is moved downwardly the sliding member has its outer end moved upwardly and outwardly and the outer end of the hook is raised.

6. The herein described knotter comprising a support, a shaft rotatably mounted therein, a tying bill at one end of the shaft, two arms disposed at right angles to each other and having their angles pivoted to the support at the rear of the shaft, a spring for normally holding one arm against the under side of the support, a finger arm carried by the support engaging arm, coacting means carried by the extreme ends of the arms and shaft to rotate the latter, a hook pivoted to one side of the support, two open frames, one upon each side of the hook having a slotted connection to the pivot securing the hook, the hook and two frames forming a thread guide, clamp and throw-off device, means for causing the hook to be raised with the two frames, and a bracket connecting the slotted frames to the upright arms, whereby as the shaft is rotated against the spring tension, the slotted frame lifts the hook and is itself raised and moved outwardly.

In testimony that I claim the foregoing as my own I have hereto affixed my signature in the presence of two witnesses.
